FOREIGN PATENT DOCUMENTS

EP 1384520 A2 1/2004

Primary Examiner — Kevin K. Rudzinski*Assistant Examiner* — Clare Ann Gannon(74) *Attorney, Agent, or Firm* — Wood Herron & Evans LLP(57) **CLAIM**

The ornamental design for a floor mat, as shown and described.

DESCRIPTION

FIG. 1 is a top plan view of a floor mat showing our new design;

FIG. 2 is an enlarged detailed view thereof, showing region 2 in FIG. 1;

FIG. 3 is a cross section view taken along line 3-3 in FIG. 2 thereof, with portions of the environment removed for ease of illustration; and,

FIG. 4 is a cross section view taken along line 4-4 in FIG. 2 thereof, with portions of the environment removed for ease of illustration.

The broken lines show portions of the floor mat that form no part of the claimed design.
